United States Patent Office

Des. 178,185
Patented July 3, 1956

178,185

DESK SET

William S. Gorham, University City, Mo.
Application July 14, 1955, Serial No. 36,980

Term of patent 7 years

(Cl. D74—1)

FIG.1.

FIG.2.

FIG.3.

FIG.4.

FIG.5.

FIG.6.

Fig. 1 is a perspective view of a desk set showing my new design;

Fig. 2 is a side elevational view thereof;

Fig. 3 is a top plan view;

Fig. 4 is a perspective view as it appears with the pen removed from the holder;

Fig. 5 is a sectional view taken on line 5—5 of Fig. 4; and

Fig. 6 is a sectional view taken on line 6—6 of Fig. 4.

I claim:

The ornamental design for a desk set, as shown.
